UNITED STATES PATENT OFFICE

109,222

DESIGN FOR A LAMP

Arthur W. Krueger, Chicago, Ill., assignor to Stephen Zidek, Riverside, Ill.

Application January 28, 1938, Serial No. 74,677

Term of patent 3½ years

To all whom it may concern:

Be it known that I, Arthur W. Krueger, a citizen of the United States, residing at Chicago, in the county of Cook and State of Illinois, have invented a new, original, and ornamental Design for a Lamp, of which the following is a specification, reference being had to the accompanying drawing, forming part thereof, in which:

I claim:

The ornamental design for a lamp, as shown.

ARTHUR W. KRUEGER.
